CLAIM

The ornamental design for a tent, as shown and described.

DESCRIPTION

FIG. 1 is a front and top perspective view of a tent, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; the bottom of the tent is flat and unornamented; and,

FIG. 7 is an enlarged partial view of a portion of the tent, taken from the left side of FIG. 1.

The dash-dot broken lines represent the boundaries of the enlarged partial views of FIG. 7 and form no part of the claimed design.

1 Claim, 7 Drawing Sheets
